UNITED STATES PATENT OFFICE

2,558,312

FLUID TRANSFER PUMP

Thomas D. Nisbet, Rocky River, Ohio

Application April 27, 1946, Serial No. 665,577

3 Claims. (Cl. 103—178)

1

My invention relates in general to fluid pumps, and in particular, to that type of pump known as a barrel dispensing pump for use at intermittent times in transferring liquid in small amounts from a large container to a smaller container. One of the objects of my invention is the provision of a fluid pump which is economical to manufacture and which will readily transfer fluid from a large container into a small container.

Another object of my invention is the provision of a fluid pump in which all the working parts are enclosed within the pump, thus making it suitable for intermittent out-of-doors use.

Another object of my invention is the provision of a fluid pump in which the packing about the lever which extends from the pump housing and which actuates the pump mechanism within the pump is not exposed to fluid pressure.

Another object of my invention is the provision of a pump in which the travel of the piston is governed by stops on the inside of the housing against which the actuating arm bumps.

Another object of my invention is the provision of a fluid pump in which the piston and piston rod have universal connection means.

Another object of my invention is the provision of a fluid pump in which the connection between the piston rod and the piston forms a valve for controlling the passage of liquid through the piston.

Another object of my invention is the provision of a fluid pump in which the piston is self-aligning with the cylinder.

Another object of my invention is the provision of a fluid pump with a piston therein which has sealing rings and a cylindrical ring about the piston.

Another object of my invention is an oscillating movement wherein all of the operating mechanism is self-contained within a cylinder taken in combination with a stuffing box which is never subjected to pressure of the liquid being pumped.

Another object of my invention is the provision of a universal connection between a piston and a piston rod which serves as a ball type valve and laps its own valve seat with each stroke of the piston.

Another object of my invention is the provision of a floating piston to which power is applied at substantially the geometrical center of the piston.

Another object of my invention is the provision of a fluid pump having a piston and piston rings including a cylindrical ring with means for lubricating the piston assembly.

2

Other objects and a fuller understanding of my invention may be had by referring to the following description and claims, taken in conjunction with the accompanying drawing, in which:

5 Figure 1 of my drawings is a cross-sectional view illustrating my preferred fluid pump;

Figure 2 is a plan view of my piston taken along the lines 2—2 of Figure 1, certain parts being omitted for clarity;

10 Figure 3 is a fragmentary view of the piston assembly in a downward stroke; and

Figure 4 is a cross-sectional view taken along the line 4—4 of Figure 1.

One of the uses of a pump of this type is where a speedy delivery is not necessary and where no measurement of the fluid or liquid being pumped is required. The main commercial use of the pump is to transfer mainly inflammable liquids from a barrel or an original shipping container into a measure or other smaller vessel. Pumps of this general class or type are often referred to as "barrel pumps."

With particular reference to the drawings, the reference character 10 represents a fluid container

25 from which fluid or liquid such as gasoline, naphtha, or other similar liquids are to be pumped. As shown in Figure 1, my pump, which is indicated by the reference character 11, is connected directly to the top of the container 10 and is adapted to be actuated by a manually operable lever 36 which is moved up and down to produce the pumping operation.

My pump comprises an intake housing 12, a discharge housing 13, and a cylinder 14 mounted

35 therebetween. The discharge housing 13 and the intake housing 12 have threaded means into which the ends of the cylinder 14 are threaded to hold the cylinder 14 therebetween. A good sealing engagement is obtained between the cylinders and the intake housing 12 and the discharge housing 13 by threading the cylinder into the housings.

30 A discharge conduit 15 may be threadably connected to the discharge housing 13, and as the pump is operated, the fluid which is being pumped is discharged out through the discharge conduit 15 into another vessel or container.

An intake conduit 16 may be threadably connected to the bottom of the intake housing 12, and when the pump is in operation the intake conduit 16 ex-

40 tends down into the container 10 for conveying liquid to the intake housing 12. A ball check valve 21 placed immediately in the intake housing 12 above the intake conduit 16 prevents the return of the flow of fluid or liquid to the container 10.

45 The ball check valve 21 may be termed

45

50

55

a one-way valve and seats itself to prevent the flow of liquid or fluid back from the pump into the chamber 10.

The lower end of the intake housing 12 is provided with two stepped threaded portions 17 and 18, whereby my pump may accommodate thread openings in the container 10 of different sizes. Original shipped or delivery containers, or drums, as now found on the market, have two sizes of threaded openings, and thus if my pump is to be connected to a container having a small opening, then the threaded portion 18 is employed, and in the event that the container has a large opening, then the threaded portion 17 is employed to connect my pump 11 to the top of the liquid container 10.

Mounted inside my cylinder 14 is a piston 24. This piston 24 is constructed from a top cup-shaped plate 25 and a bottom cup-shaped plate 26. Each of these plates 25 and 26 have a center opening 27 therein through which piston rod 28 extends. As is best illustrated in Figure 2, the top cup-shaped plate 25 has a bottom portion 29 with the side or cylindrical flange portion 30 thereabout. The bottom plate 26 has a bottom portion 31 with a cylindrical flange 32 thereabout. Radial end flanges 59 extend about the cylindrical flanges 30 and 32. The bottom portions 29 and 31 have raised bosses 33 and 34, whereby the top and bottom plates may be fastened together with a space 40 therebetween. The bosses 33 on the top plate and 34 on the bottom plate separate the bottom portions 29 and 31 when the cup-shaped plates are put back to back. The plates may be fastened together by spot welding these bosses 33 and 34 together. The top plate 25 has openings 35 in the bottom portion 31 between these bosses 33. A plan view of the top plate, to better illustrate the preferred arrangement of these bosses 33 and openings 35 therebetween, is best illustrated in Figure 2 of my drawings.

Double sealing rings are used in the piston. Since this is the most vulnerable part of any pump, the double sealing rings insure longer life because the pump will function successfully even though one ring becomes damaged or broken. It is understood that I do not intend to limit my invention to a piston with which double sealing rings are used, but am using this to better describe the preferred design of my pump. The double sealing rings comprise an expansion ring 37 and an expansion ring 38 with a cylindrical ring 39 therebetween. The expansion rings 37 and 38 engage the wall of the cylinder 14, and the cylindrical ring 39 between the expansion rings 37 and 38 engages the cylindrical flanges 30 and 32 of the piston 24. The position of these rings 37, 38 and 39 is best illustrated in Figures 1 and 3 of my drawings.

In constructing the piston 24 the cylindrical ring 39 may be used as a jig for aligning the piston plates 25 and 26. The cylindrical ring has an inside diameter substantially the same as the outside diameter of the cylindrical flanges 30 and 32 to provide a slip fit therebetween. The top plate 25 may be slipped into one side of the cylindrical ring 39, and the bottom plate 26 slipped into the other side of the cylindrical ring 39. This cylindrical ring 39 may be constructed from a section of pipe, or it may be made of flat stock rolled into the desired shape. After the plates 25 and 26 have been inserted in the sides of the cylindrical ring with the bottom portions of the plates separated by the

bosses 33 and 34, these plates may be welded together at the point of engagement of the bosses to form the piston 24. The cylindrical ring 39 aligns the top plate 25 with the bottom plate 26 and extends about the space 40 between the bottom portions 31 and 29 of the plates 25 and 26. The cylindrical ring 39 has a width greater than the distance between the bottom portions 29 and 31 of the plates 25 and 26 which form the piston 24. Lubrication about the cylindrical ring 39 may be obtained from the fluid or liquid flowing through the space 40 between the plates of the piston. The expansion rings 37 and 38, one on each side of the cylindrical ring 39, may be any suitable split piston ring which normally expands outwardly against the cylinder wall about the piston. These piston rings 37 and 38 may be inserted about the piston and one on either side of the cylindrical ring 39 as the piston is inserted in the cylinder 14. The expansion rings 37 and 38, while engaging the cylinder wall of the cylinder 14, also fit between the side edges 41 of the cylindrical ring 39 and the radial end flanges 59 of the top and bottom plates 25 and 26. The combination of these rings 37 and 38 along with the cylindrical ring 39 seal the space 40 between the top plate 25 and the bottom plate 26 and also seal between the piston and the cylinder wall.

30 The piston rod 28, which extends through the center opening 27 in the piston 24 and is universally connected thereto, may be preferably constructed from a rod. The piston rod 28 has a shoulder 45 with a threaded extended portion 46 on the end thereof which extends through the piston 24. The threaded extended portion 46 has a smaller diameter than the main body portion 47 of the piston rod 28. The other end of the piston rod 28 has a flat portion 48 with an opening therethrough to provide means for hingedly fastening an actuating arm 50 thereto.

A bottom valve member 53 and a top member 54, spaced by a spacer 55, extend about the threaded extended portion 46 of the piston rod 28 and are held thereon by a nut 56. The bottom valve member 53 has a flat surface 57 on one side thereof which abuts against the shoulder 45 and a curved surface 58 which engages the center opening 27 in the bottom plate 26. 45 The edge of the opening 27 in the bottom plate forms a valve seat, against which the curved surface 58 of the bottom valve member 53 seats itself to close the valve. This bottom valve member 53 preferably has a spherical surface and may be constructed from a ball or small sphere. When the bottom valve member 53 engages the bottom plate 26, while the piston is moving upward or toward the discharge housing 13, the valve is closed.

60 Similarly, the top member 54 may be constructed from a spherical segment or from a ball and is disposed to engage about the center opening in the top plate 25 when the piston is being moved downward. The spacer 55, between the bottom valve member 53 and the top member 54, has a length sufficient to prevent engagement of the bottom valve member 53 with the bottom plate 26 while the top member 54 is in engagement with the top plate 25. Although I have shown the top member 54 to be a spherical segment, and preferably designed it such for construction from the sphere or ball from which the bottom valve member 53 is constructed, it is understood that other suitable shaped members may be employed.

To reciprocally move the piston 24 in the upward and downward strokes within the cylinder 14, I use the lever arm 36 which has a shaft portion 61 extending within the intake housing 12. As is shown in my drawings, the shaft portion 61 is at an angle to the lever 36, whereby it will be partially oscillated when the lever is moved up and down. The shaft portion 61 has non-circular shape and carries the shaft end 51 of the actuating arm 50 which actuates the piston rod 28. The shaft end 51 of the actuating arm 50 has a non-circular opening therein to cooperate with the shaft portion 61, whereby when the lever 36 is manually moved up and down, the actuating arm 50 is hingedly connected by means of a pin 62 to the piston rod flattened portion 48. The actuating arm 50 may be constructed from two flat strips of metal which may be spot welded together or joined by other suitable means. The two flat strips of metal are separated on the piston end 52 with the strips of metal extending on opposite sides of the flat portion 48 of the piston rod 28.

A stop 63 and a stop 64, on the inside of the intake housing 12, limit the oscillating movement of the actuating arm 50 to control the length of the piston stroke in either direction. These stops 63 and 64 may be cast as a part of the intake housing 12. When the lever 36 is moved down to move the piston 24 up, the actuating arm 50 bumps against the stop 63 to prevent further movement of the piston in the upward direction. When the lever is moved upward to move the actuating arm, and thereby the piston, in the downward direction toward the intake housing, the actuating arm 50 bumps against the stop 64 to prevent further movement of the piston in the downward direction. The piston travel or stroke in either direction is thus controlled by means which cannot result in any damage to the piston or piston rod.

To prevent escape of liquid or fluid about the shaft portion 61 of the lever 36 where it enters the lever support portion 67 of the intake housing 12, I have employed a packing nut 65, and packing or stuffing 66. This packing or stuffing 66 may be of any suitable material which may readily compress about the shaft portion 61 when the packing nut 65 is tightened into the lever support portion 67 of the intake housing 12. By extending the lever 36 into the intake housing 12 and fastening the actuating arm to it on the intake side of the piston, I have provided a stuffing box about the lever which is never subjected to the pressure of the liquid or fluid being pumped. Stuffing or packing, when not subjected to the high pressure of the liquid or fluid being pumped, will form a fluid-tight seal about the lever for a much longer period of time.

Washers 69 may be inserted, one on each side of the actuating arm 50 and on the shaft portion 61 of the lever arm 36 to prevent play in the movement of the actuating arm 50. These washers 69 and the actuating arm 50 may be assembled onto the shaft portion 61 as it is being inserted into the lever support portion 67 of the intake housing 12. Inside shoulders 70 of the lever support portion 67 are substantially parallel to the plane of movement of the actuating arm 50. The washers 69, placed between the actuating arm 50 and the shoulders 70, prevent sidewise movement between the actuating arm and the shaft portion 61.

Figure 1 of my drawing illustrates the position of the piston at the top of a stroke. In the upward stroke, the piston 24 has pulled fluid or

liquid through the intake conduit 16 and into the intake housing 12 and the cylinder 14. This liquid is prevented from moving back into the container 10 by the ball check valve 21 in the intake housing 12. The lever 36 is then moved upward to pull the piston 24 downward or toward the intake housing 12. The connection between the piston rod 28 and the piston 24 while the piston rod 28 is pulling the piston 24 in this downward direction, is best illustrated by Figure 3 of my drawing. The top member 54 engages the top plate 25 of the piston 24 and about the center opening 27 to form a connection means between the piston 24 and the piston rod 28 whereby the piston rod pulls the piston downward. The bottom valve member 53 is away from the valve seat about the opening 27 in the bottom plate 26. Fluid in the bottom of the cylinder and in the intake housing 12 passes through the opening 27 in the bottom plate 26 through the space 40 between the plates 25 and 26 and through the openings 35 in the top plate 25. When the piston has reached the bottom of the stroke, the actuating arm 50 bumps against the stop 64 to prevent further movement in the downward direction toward the intake housing. The liquid or fluid which was below the piston or on the intake side, has now passed through the piston and is on the discharge side of the piston.

When the lever handle is pushed down, the piston rod moves the piston upward or toward the discharge housing 13 to force the liquid or fluid on that side of the piston out of the pump and at the same time to pull more liquid through the intake conduit 16 into the pump. The bottom valve member 53 on the piston rod 28 engages the bottom plate 26 of the piston 24 and seats itself about the opening 27 to form a closed valve while the piston is being moved upward and toward the discharge housing 13. This bottom valve member 53 thus serves the dual purpose of providing a ball universal connection between the piston and the piston rod and also as a ball-type valve which laps its own seat with each stroke of the piston. Since the bottom valve member 53 seats against the edge of the center opening 27 in the bottom of the piston, it closes the valve to prevent passage of fluid or liquid through the piston. Thus as the piston is raised or moved in the upward direction it forces liquid outward through the discharge conduit 15 under a pressure and at the same time pulls more liquid or fluid through the intake conduit 16 into the pump.

I have provided for what may be termed a "floating" piston by universally connecting the piston rod to the piston at substantially the geometrical center of the piston. The power to the piston is applied at substantially this geometrical center of the piston. The universal connection between the piston rod and the piston prevents unnecessary sidewise forces between the piston and the cylinder. With this universal connection substantially at the geometrical center of the piston, the piston rod may swing with respect to the piston in any direction and yet move the piston upward or downward in the cylinder. The piston rings, backed up by the cylindrical flanges about the piston prevent the piston from tipping as it is reciprocally moving in the cylinder.

Although I have described my invention with a certain degree of particularity in its preferred form, it is understood that the present disclosure 75 of the preferred form has been made only by

way of example and that numerous changes in the details of construction and the combination and arrangement of parts may be resorted to without departing from the spirit and the scope of the invention as hereinafter claimed.

What is claimed is:

1. The combination of an improved swingable piston and an improved piston rod adapted to reciprocally move the piston in a first and in a second direction in a pump cylinder, said piston comprising a first and a second plate each having an opening in the center thereof, means for fastening the plates together and for providing space therebetween through which fluid may pass, said second plate having at least a second opening through which fluid may pass from the space between said plates, said piston and said swingable piston rod having universal and swingable connection means including a valve with a valve seat defined by the center opening in the first plate and a valve member universally seatable therein, said valve member seating in said valve seat to close the valve and prevent fluid passing therethrough into the space between the plates while the piston rod moves the piston in the first direction, said valve member moving from the valve seat to open the valve and permit fluid to pass therethrough into the space between the plates while the piston rod moves the piston in the second direction.

2. In a valved piston for a fluid pump, a first and a second plate each having an opening in the center thereof, means for fastening the plates together and for providing space therebetween through which fluid may pass said second plate having at least a second opening through which fluid may pass from the space between said plates, a pair of spaced members adapted to be carried by a piston rod one of said members constituting a valve member, each of said members having a substantially spherical surface with the spherical surface on one member facing the spherical surface on the other member, the spherical surface on said valve member being positioned to seat in the opening in the center of the first plate.

3. The combination of an improved piston

and an improved swingable piston rod adapted to reciprocally move the piston in a first and in a second direction in a pump cylinder, means for fastening the plates together and for providing space therebetween through which fluid may pass, said first plate having an opening through which fluid may pass into the space between said plates, said second plate having an aperture means through which fluid may pass from the space between said plates, said piston and said swingable piston rod having universal and swingable connection means to reciprocally move said piston in said first and second directions and including a valve with a valve seat defined by said opening in the first plate and a valve member universally seatable therein, said valve member seating in said valve seat to close the valve and prevent fluid passing therethrough into the space between the plates while the piston rod moves the piston in the first direction, said valve member moving from the valve seat to open the valve and permit fluid to pass therethrough into the space between the plates while the piston rod moves the piston in the second direction.
